FIG. 3

Goodman Gafinowitz
Inventor

FIG. 4
By *Geot. P. Kimmel*
Attorney

UNITED STATES PATENT OFFICE.

GOODMAN GAFINOWITZ, OF BURLINGTON, VERMONT.

IDENTIFICATION DEVICE.

1,350,275.

Specification of Letters Patent. Patented Aug. 17, 1920.

Application filed May 24, 1918. Serial No. 236,297.

To all whom it may concern:

Be it known that I, GOODMAN GAFINOWITZ, a citizen of the United States, residing at Burlington, in the county of Chittenden and State of Vermont, have invented 5 certain new and useful Improvements in Identification Devices, of which the following is a specification.

This invention relates to improvements in 10 identification means and it is the principal object of the invention to provide a novel form of identification device particularly adapted for use in connection with the handles of canes, umbrellas, and other articles 15 whereby an owner thereof can readily identify the same.

Other objects will be in part obvious and in part pointed out hereinafter.

The improvements in the details and arrangement of parts will be apparent from 20 an inspection of the accompanying drawings, in connection with the specific description hereinafter contained and wherein the preferred embodiment of the invention is 25 disclosed for the purpose of imparting a full understanding of the same.

In the drawings:

Figure 1 is a side elevation of an umbrella handle provided with the improved identifying device,

Fig. 2 is a horizontal section therethrough,

Fig. 3 is a fragmentary vertical section through the same, and

Fig. 4 is an enlarged fragmentary horizontal or transverse section through the handle.

Having more particular reference to the drawings, in connection with which like reference characters will designate corresponding parts throughout the several views, 1 represents the umbrella handle in its entirety, the longitudinal portion of which is recessed as at 2 to provide a substantially rectangular seat whereby to permit the arrangement of a card 3 therein, said card having the name of the owner or other suitable identification matter printed on the outer face thereof and receiving a transparent piece 3' thereover for an obvious purpose. 10 Grooves indicated by the numeral 4 are formed in the side walls of the recessed portion 2 and are adapted to receive a locking device 5 formed desirably from a single piece of spring wire shaped to provide an open or 15 split rectangular loop, with the slit positioned at one end of the loop. Obviously, by

arranging the card in the recessed portion 2, then arranging a protecting transparent piece 3' therein and finally engaging the locking device 5 with the grooved walls 60 thereof, displacement of said card irrespective of the positioning of the handle 1 will be prevented, thereby affording an effectual form of identification means for the umbrella so provided.

For the purpose of receiving such data as is necessary for the quick identification of the articles to which the device is attached, it is desirable that the card be of the elongated rectangular form such as suggested in 70 Figs. 1 and 3. Obviously the wire loop 5 conforms to the internal contour of the recess and due to its polygonal shape it is prevented from rotary movement therein or any other such movement which might tend 75 to eventually result in its displacement. The terminals of the wire at the split in the loop are directed inwardly toward the center of the recess in the handle 1, terminating slightly beyond the walls of said groove 80 in order that the terminal of a sharp pointed instrument such as the blade of a knife may be readily inserted thereunder to facilitate removal of the loop from the recess. The inwardly turned ends of the wire lie 85 upon the transparent piece 3' and are removed inwardly from the plane of the external surface of the handle 1 so as not to be engaged and displaced during casual manipulation of the handle.

I of course desire to have it understood that I do not intend to limit the scope of application of the invention to the handle of an umbrella, cane, or similar article, but may arrange the same on any articles of 95 personal property, such as conditions or preference may dictate.

Manifestly, the construction shown is capable of considerable modification and such modification as is within the scope of 100 my claim, I consider within the spirit of my invention.

I claim:

The combination with a handle substantially circular in cross section having a 105 polygonal recess provided in the side and end walls thereof with a continuous groove, of a card correspondingly shaped to the recess and fitted within the same inwardly relative to said groove, a transparent cover 110 superposed upon the card to lie in a plane inwardly with respect to said groove, and a

resilient split wire loop corresponding to the polygonal shape of the recess to prevent movement of the loop therein and of slightly greater size than the groove for snapping engagement therewith, the ends of the wire being turned outwardly of said groove to-

ward the center of the recess and lying wholly within the plane of the external surface of the handle.

10

In testimony whereof, I affix my signature hereto.

GOODMAN GAFINOWITZ.
